CLAIM

The ornamental design for an in-line staged vehicle, as shown and described.

DESCRIPTION

FIG. 1 is a front perspective view of an in-line staged vehicle showing my new design, the opposite side being a mirror image thereof;

FIG. 2 is a front view thereof;

FIG. 3 is a rear view thereof;

FIG. 4 is a side view, the opposite side being a mirror image thereof;

FIG. 5 is a bottom view thereof;

FIG. 6 is a front perspective view of the in-line staged vehicle of FIG. 1, with the first and second stages separated, the opposite side being a mirror image thereof;

FIG. 7 is a bottom view of the in-line staged vehicle of FIG. 1, with the first and second stages separated; and,

FIG. 8 is a rear view of the second stage of the in-line staged vehicle of FIG. 1.

The structural elements in the drawing depicted by means of broken lines have been shown for the purpose of illustrating portions of the in-line staged vehicle which form no part of the claimed design.
